[57] CLAIM

The ornamental design for a chip remover tool, as shown and described.

DESCRIPTION

FIG. 1 is a top plan view of a chip remover tool, showing my new design;

FIG. 2 is a front elevational view thereof;

FIG. 3 is a bottom plan view thereof;

FIG. 4 is a right-side elevational view thereof;

FIG. 5 is a rear elevational view thereof;

FIG. 6 is a front elevational view of a second embodiment of my new design;

FIG. 7 is a rear elevational view of a second embodiment of my new design;

FIG. 8 is a cross-sectional view taken at line 8—8 in FIG. 2 and viewed in the direction of the arrows.

The appearance of the top of the second embodiment is the same as that shown in FIG. 1 for the first embodiment.

The appearance of the bottom of the second embodiment is the same as that shown in FIG. 3 for the first embodiment.

The dotted outline in FIGS. 1 and 5 indicates a handle and is shown to illustrate the environment, but is not a part of the design.
